UNITED STATES PATENT OFFICE

ALLEN WEST, OF BRIGHTON, ENGLAND

OIL IMMERSSED SWITCH

Application filed April 29, 1929, Serial No. 359,061, and in Great Britain May 16, 1928.

This invention relates to oil immersed switches and has reference particularly to the venting of such switches.

The difficulty has been experienced in vented oil switches that explosions, or sudden pressure rises, due to a short circuit result in the discharge of oil through the vent openings, which are usually formed by a series of superposed plates separated one 10 from the other sufficiently to permit of the escape of the gases.

The object of the present invention is to provide means for preventing this discharge of oil while permitting the gases to escape.

15 The invention consists broadly in the provision, in association with the vent, of a chamber into which the oil can be thrown by the explosion and from which it can then drain back into the switch.

20 Two of the forms which the invention may take are illustrated in the accompanying drawings in which,

Figure 1 is a vertical section through one embodiment of the invention, and

25 Figure 2 is a plan of the same with interior parts indicated in dotted lines.

Figure 3 is a vertical section of another form of the invention.

In the construction shown in Figure 1, a 30 metal dome 1 has integral with it an inwardly projecting horizontal annulus 2 provided at its inner edge with a vertical flange 3. An annular oil collecting channel 4 is thus formed within the dome. The lower sur-

35 face of the annulus 2 bears on the uppermost member of a pile of annuli 5 which alternate with washers or strips 6 to form a vent of more or less usual form. For purposes of illustration, these washers are shown somewhat 40 exaggerated in thickness in the drawings.

The pile of annuli and their spacing members rest upon the edge of an opening 8 in the cover 7 of the switch housing and are held in position between the lower surface of 45 the annulus and the upper surface of the switch housing cover by hollow bolts 9, the holes 10 through which constitute oil draining tubes.

50 The upper end of each of these bolts is threaded into a hole in the annulus 2 and lies

flush with the upper surface of the annulus; the lower end passes through a hole in the housing and is secured by a nut 11.

In other words the annular venting plates and their spacing members are clamped between the dome member and the top of the switch housing, tubular bolts being employed to provide the necessary drainage pipes.

The lower edge of the dome is extended downwards on one side of the vent at 12 to 60 protect the operator from flaming gas forced through the vent by explosions within the switch housing.

Two dished circular baffle plates 14 and 15 are provided beneath the opening 8 in the switch housing and these baffles are carried on a spindle 13 screwed into the top of the dome and are secured thereon by nuts 16 and 17.

It will be seen that by means of this arrangement the gases will be allowed to escape freely through the annular vent while any oil thrown up by the explosion and not caught by the baffle plates will collect in the channel 4 and drain back into the switch 75 housing through the hollow bolts 9.

A simpler form of construction is shown in Figure 3, the switch housing 20 has an external flange 27 and the dome member 21 is provided with an external flange 22

The pile of annular venting plates 5 and their members 6 are secured between these two flanges by bolts 29 and nuts 31. Draining holes 30 are cut through the pile of plates. The dome member has an additional vertical flange 32 on one side to protect the operator. Baffle plates may be used similar to those shown in Figure 1.

What I claim and desire to secure by Letters Patent is:—

1. A vent for oil immersed switches comprising a laminated structure applied to an opening in the top of the switch containing casing, said laminated structure forming a vent for the escaping gases, an opening 95 through the laminated structure through which oil displaced by rises in pressure passes upwardly, a dome above said opening adapted to deflect the displaced oil into a channel above the laminated structure, and drainage 100

holes leading from said channel back to the switch casing.

2. A vent for oil immersed switches comprising a laminated structure applied to an opening in the top of the switch containing casing, said laminated structure forming a vent for the escaping gases, an opening through the laminated structure through which oil displaced by rises in pressure passes upwardly, baffle plates beneath said opening, a dome above said opening adapted to deflect the displaced oil into a channel above the laminated structure, and drainage holes leading from said channel back to the switch casing.

3. A vent for oil immersed switches comprising a laminated structure applied to an opening in the top of the switch containing casing, said laminated structure forming a vent for the escaping gases, an opening through the laminated structure through which oil displaced by rises in pressure passes upwardly, a dome above said opening adapted to deflect the displaced oil into a channel above the laminated structure, a spindle depending from the top of said dome, baffle plates carried on the lower end of said spindle and located beneath said opening and drainage holes leading from said channel back to the switch casing.

4. A vent for oil immersed switches comprising a series of superimposed annuli, washers separating and alternating with said annuli, an opening in the top of the switch casing which said annuli and said washers border, a dome structure having a flange abutting upon the pack of annuli and washers, bolt devices for clamping the dome, annuli and washers to the top of the switch casing and holes passing through said annuli and said washers through which oil thrown up into the dome drains back into the switch casing.

5. A vent for oil immersed switches comprising a series of superimposed annuli, washers separating and alternating with said annuli, an opening in the top of the switch casing which said annuli and said washers border, a dome structure having a flange abutting upon the pack of annuli and washers, bolt devices for clamping the dome, annuli and washers to the top of the switch casing and holes passing through said bolts through which oil thrown up into the dome drains back into the switch casing.

6. A vent for oil immersed switches comprising a series of superimposed annuli, washers separating and alternating with said annuli, an opening in the top of the switch casing which said annuli and said washers border, a dome structure having a flange abutting upon the pack of annuli and washers, a spindle depending from said dome, baffle plates carried upon the lower end of said spindle and located beneath the opening in the top

of the switch casing, bolt devices for clamping the dome, annuli and washers to the top of the switch casing and holes passing through said annuli and said washers through which oil thrown up into the dome drains back into the switch casing.

In witness whereof, I affix my signature.

ALLEN WEST.
